SHANK PIECE FOR SHOES

Filed April 10, 1929

FIG. 1

FIG. 2

INVENTOR
J. W. LAKE
BY J. G. Cook
ATTORNEY

UNITED STATES PATENT OFFICE

JOHN W. LAKE, OF ST. LOUIS, MISSOURI, ASSIGNOR TO BOYD-WELSH SHOE COMPANY, OF ST. LOUIS, MISSOURI, A CORPORATION OF MISSOURI

SHANK PIECE FOR SHOES

Application filed April 10, 1929. Serial No. 353,975.

This invention relates generally to shank pieces for shoes, and particularly to an improved article of this type provided with yieldable supports for the heel and the metatarsal arch of the foot of the wearer of a shoe equipped with the improved shank piece, the predominant object of the invention being to provide a shank piece which will serve to render a shoe equipped therewith more comfortable to the wearer than were shoes provided with shank pieces of the type formerly employed.

Fig. 1 is a fragmentary section of a shoe provided with one of my improved shank pieces.

Fig. 2 is a plan view of the improved shank piece.

In the drawing, wherein is shown for the purpose of illustration merely, one embodiment of the invention, A designates a shoe. The shoe A is a lady's shoe of the high or French heel type, and comprises an outsole B, an insole C, and a heel D. The thickness of material E represents the lasting allowance of the upper, said lasting allowance being interposed between the outsole B and the insole C in the usual manner.

1 designates my improved shank piece, which is interposed between the outsole B and the insole C. As shown in Fig. 2, the shank piece is shaped to correspond to the horizontal shape of the shoe at the outsole and insole thereof, and said shank piece extends from the rear or heel portion of the shoe to a point a slight distance forward of the break F in the outsole B. The shank piece is formed of leather or any other suitable material, and at the heel portion thereof said shank piece is gouged out to provide a recess 2 which extends substantially the entire width of the shank piece and forwardly from the rear edge of said shank piece to a point a slight distance forward of the front portion of the heel D. Also, at the forward portion of the shank piece same is gouged out to provide a recess 3. The last mentioned recess is more or less circular when viewed in plan, and is of less width than the shank piece, and is disposed at the approximate transverse cen-

ter of said shank piece at the extreme forward end thereof.

Disposed within the recess 2 at the heel portion of the shank piece is a filler or pad 4 of suitable yieldable material, such as sponge rubber, cork, felt, etc., said filler 4 being co-extensive with the recess and being of a thickness approximately equal to the depth of said recess. Also, I employ a similar filler or pad 5 which is located within the recess 3 at the forward portion of the shank piece, said filler 5 being co-extensive with the recess 3. Unlike the filler 4, the filler 5 bulges upwardly at its center, as shown in Fig. 1, so that at said center of said filler same is of slightly greater thickness than the depth of the recess 3. In other words, at the approximate center of the filler 5 the top face thereof is extended upwardly beyond the top surface of the shank piece. Because of the cross-sectional shape of the filler 5, the insole C is gouged out slightly to provide a recess 6 into which the upwardly bulged top surface of the filler 5 extends, as shown in Fig. 1. The fillers 4 and 5 are secured in place within the recesses 2 and 3 in any suitable manner.

In constructing a shoe equipped with one of my improved shank pieces, the outsole, insole, and lasting allowance are secured together in the manner common to shoes of the type illustrated. Also, the heel D is secured to the shoe proper by means of the usual fastening elements 7, which are usually in the form of nails, and these fastening elements 7 are extended through the shank piece 1, as shown in Fig. 1.

In the use of shoes having my improved shank pieces as parts thereof, the filler 4 at the heel portion of each of the shank pieces serves as a yieldable support for the heel of the wearer of the shoe, and because of its presence makes the shoe far more comfortable to wear than the shoes constructed as heretofore. Also, the filler 5 at the forepart of the shank piece acts as a yieldable support for the metatarsal arch of the wearer's foot, and thus makes the shoe more comfortable to wear and eliminates trouble resulting from bunions and similar sources of foot discomfort.

I claim:

1. A shank piece comprising an element shaped so as to be capable of being interposed between the outsole and insole of a shoe, said element being provided with a recess at the heel portion thereof, said recess being extended substantially the entire width of the shank piece and forwardly from the rear edge thereof, and a yieldable pad disposed within said recess.
- 10 2. A shank piece comprising an element shaped so as to be capable of being interposed between the outsole and insole of a shoe, said element being provided with a recess at the heel portion thereof, said recess being extended substantially the entire width of the shank piece and forwardly from the rear edge thereof, and a yieldable pad disposed within said recess, the thickness of said pad being approximately the same as the depth of said recess.
- 15 3. A shank piece comprising an element shaped so as to be capable of being interposed between the outsole and insole of a shoe, said element being provided with a recess at the heel portion thereof and with a second recess at the forward portion of said element, and yieldable pads disposed within the respective recesses.
- 20 4. A shank piece comprising an element shaped so as to be capable of being interposed between the outsole and insole of a shoe, said element being provided with a recess at the heel portion thereof and with a second recess at the forward portion of said element, and yieldable pads disposed within the respective recesses, the pad in the first mentioned recess being of a thickness substantially the same as the depth of the recess and the pad in the second mentioned recess being of a thickness slightly greater than the depth of the recess so that a portion thereof projects beyond the surface of the shank piece.
- 25 5. A shoe including an outsole, an insole, and a shank piece interposed between said outsole and said insole, said shank piece comprising an element provided with a recess formed therein at the forward portion thereof, and a yieldable pad disposed within said recess, a portion of said pad being of a thickness slightly greater than the depth of the recess so that said portion of said pad extends beyond the surface of said shank piece, and said insole being provided with a recess which receives said extended portion of said pad.
- 30 6. A shoe including an outsole, an insole, and a shank piece interposed between said outsole and said insole, said shank piece comprising an element provided with a recess formed therein at the forward portion thereof, a yieldable pad disposed within said recess, a portion of said pad being of a thickness slightly greater than the depth of the recess so that said portion of said pad extends

beyond the surface of said shank piece, and said insole being provided with a recess which receives said extended portion of said pad, said shank piece being provided with a second recess at the heel portion thereof, and a yieldable pad disposed within the second mentioned recess.

In testimony that I claim the foregoing I hereunto affix my signature.

JOHN W. LAKE.
